CLAIM

The ornamental design for a chair, as shown and described.

DESCRIPTION

FIG. 1 is a right front perspective view of a preferred embodiment of a chair embodying my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; the opposite side being a mirror image;

FIG. 7 is a right front perspective view of an alternate embodiment of a chair embodying my new design;

FIG. 8 is a top plan view of the alternate embodiment; and,

FIG. 9 is a rear elevational view of the alternate embodiment.

FIG. 1

FIG. 2

FIG. 3

FIG. 4

FIG. 5

FIG. 6

FIG. 7

FIG. 8

FIG. 9
